UNITED STATES PATENT OFFICE.

CHARLES F. LARSEN, OF NEW YORK, N. Y.

COVER FOR CANS.

Application filed November 27, 1926. Serial No. 151,109.

This invention relates to cans containing emulsified spiritus or so-called "solid fuel" for cooking purposes, and has for its principal object to provide a cover for such cans with means for lighting the fuel, which means simultaneously serve the purpose of removing the cover from the can.

With this end in view, my invention consists essentially of a handle suitably fastened to the cover of a can, the handle being of such a length as to easily pry the cover off the can, and of means, forming part of the handle, for igniting the contents of the can, all embodied integrally with the cover, by the use of which the employment of the customary can opener and the use of matches or separate igniting devices are entirely eliminated.

The invention is illustrated by the aid of the accompanying drawings in which preferred embodiments of the same are shown, and in which

Fig. 1 is a plan view of a can having a cover embodying my improvements;

Fig. 2 is a vertical longitudinal sectional view along the plane of line 2—2 in Fig. 1;

Fig. 3 is a vertical cross sectional view of the cover only along the plane of line 3—3 in Fig. 1;

Fig. 4 is a fragmentary cross sectional view along the plane of line 4—4 in Fig. 3;

Fig. 5 is a vertical cross sectional view similar to that shown in Fig. 3, but illustrating a modified form of an igniting device and of a support for the handle;

Fig. 6 is a horizontal sectional view along the plane of line 6—6 in Fig. 5; and

Fig. 7 a fragmentary vertical sectional view along the plane of line 7—7, Fig. 5, showing the support for the handle in elevation.

Like numbers of reference denote similar parts throughout the several views and the following specification.

10 is a can made of sheet metal, having a bottom 11, a circular side 12, and a top 13 provided with an opening 14 defined by a downwardly projecting circular flange 15. 16 is emulsified spiritus or so-called "solid fuel" with which the can is filled.

17 is a cover consisting, preferably, of a circular plate 18 having an upwardly extending circular side 19 and an outwardly disposed ring 20. Side 19 is adapted to fit within flange 15 of the can, and ring

20 to rest upon it, thereby closing the opening 14. 21 and 22 are upwardly extending standards or lugs made, preferably, by doubling over extensions at 23 at opposite extreme edges of the cover, as clearly shown in Fig. 3. The upper end of lug 22 is bent into a tubular socket at 24. 25 is a handle made up of, preferably, a single piece of spring wire 26 in the shape of levers 27 and 28, joined by a circular loop 29. The end of lever 27 is bent downwardly at right angles at 30 to be held tightly within tubular socket 24, and then at 31 horizontally at right angles to form a shaft 32 which has one end journaled within lug 21 at 33. 34 is a slot in lug 21 to facilitate the inserting of the end of the shaft within it. 35 is a roller, loosely mounted over shaft 32 made, preferably, of a very hard metal, and having a rough, rasp-like outer surface. The end of lever 28 is bent downwardly at right angles at 36 and threaded at 37 to receive a coupling 38 which serves to fasten a soft metal pin 39 to the end of the downwardly bent end 36 of the lever 28. The pin 39 rides upon the roller 35. Levers 27 and 28 are each provided with loops 40 and 41 which serve as finger rests when operating the device.

In Figs. 5, 6 and 7 is shown a modification of the construction of the cover just described, which consists primarily in substituting a flat form of friction device for the roller 35 referred to herein. In these figures, the lugs 21 and 22 are not made out of one piece with the cover 18, but they are connected together by a strip 42 which is welded or otherwise suitably secured to the cover 18. A flat piece 43 of very hard metal, like roller 35, also having a rough rasp-like surface, is supported over the shaft 32. Recess 44 at one end of piece 43 engaging notches 45 of lug 21, and recess 46 straddling wire 31 at the other end, permit piece 43 to move laterally; the pressure exerted by the lever 28 which is made of spring wire, against the pin 39 resting upon the piece 43 and the projection of socket 24 of lug 22 prevent vertical displacement of piece 43.

The operation of the device is, as follows:

When it is desired to open the can and use the fuel, downward pressure is exerted upon levers 27 and 28, the hand of the user spanning both levers, his thumb and forefinger

resting against the outside of loops 40 and 41, when the cover will easily be pried off the can. The cover is then reversed, that is held over the open end of the can, upside down, and lever 28 is moved inwardly toward lever 27 (as indicated in dotted lines in Fig. 1) by the pressure of the thumb, which causes the soft metal pin 39 to be drawn over the hard roller 35 or flat piece 43, if the modified construction is used. The frictional contact between the soft pin 39 and the hard rough surface of roller 35 or piece 43 cause sparks to form which, the cover acting as a shield, are directed downwardly to the fuel in the can which is thereby ignited. Roller 35 and piece 43 are loosely mounted so as not to present the same surface to the soft metal pin 39 when the same is drawn over them, which tends to increase the lasting qualities of these friction members.

My invention is particularly advantageous for use by campers or others wishing to light the fuel in the open where a breeze is blowing or where a strong draft is prevailing. The cover, after having been removed from the can, is inverted and held with the igniter close to the open end of the can and the fuel. In this position the cover acts as a shield directing the sparks into the fuel and, by being manipulated to a suitable position, will prevent the wind or draft blowing out the flame in its initial stage.

While I have shown two modifications of the igniting device proper, I do not wish to limit myself to either of the two or any combination of their essential elements, but wish to cover broadly any form of frictional igniter, fastened in a suitable manner to the cover of a can which may be removed from the can by pressure upon the operating medium of the igniter, as more clearly set forth in the appended claims.

What I claim as new, is:

1. A can having a removable cover, an igniting device fastened to the cover, a lever projecting from the said cover adapted to remove the cover entirely from the can, and

means optionally coacting with the said lever to operate the said igniting device. 50

2. A can having a removable cover, an igniting device fastened to the cover, a pair of lever arms projecting from the said cover adapted to pry the cover off the can, one of the said lever arms being in sliding contact with the said igniting device and having means to operate the same, the said cover protecting from wind a flame started by the said igniting device. 55

3. A can having a removable cover, a 60 sparking device, having a friction element, fastened to the cover, a pair of lever arms projecting from the said cover adapted to to pry the cover off the can, one of the said lever arms being adapted to slidingly 65 contact with the said friction element for the purpose of emitting sparks therefrom, the said cover, when inverted, acting as a shield for the said sparks.

4. A can having a removable cover, a 70 friction element mounted upon the cover, a lever secured to the said cover adapted to pry the cover off the can, the said lever having means slidingly engaging the said friction element for the purpose of emitting 75 sparks therefrom, the said cover, when inverted, aiding the starting of a flame by the said sparks.

5. A can having a removable cover, lugs on the cover, a pair of handle bars formed by a single piece of wire having one end 80 projecting through the said lugs, a friction member loosely supported between the said lugs by the said end of the wire, the other end of the wire, being the terminal of one 85 of the handle bars, engaging the said friction member to cause sparks to be emitted therefrom, when brought in sliding contact therewith, the said handle bars being adapted to pry the cover off the can, the 90 said cover acting as a shield for the said sparks.

In testimony whereof I have hereunto set my hand.

CHARLES F. LARSEN.
